(57) **CLAIM**

We claim the ornamental design of the random orbital sander, as shown and described herein.

DESCRIPTION

FIG. 1 shows a perspective view of a random orbital sander; FIG. 2 shows a left side view of a random orbital sander shown in FIG. 1;

FIG. 3 shows a front view of a random orbital sander shown in FIG. 1;

FIG. 4 shows a right side view of the random orbital sander shown in FIG. 1;

FIG. 5 shows a back view of a random orbital sander shown in FIG. 1;

FIG. 6 shows a bottom view of a random orbital sander shown in FIG. 1; and,

FIG. 7 shows a top view of a random orbital sander shown in FIG. 1.
